[57] CLAIM

The ornamental design for a trailing dethatcher, substantially as shown and described.

DESCRIPTION

FIG. 1 is a reduced right side perspective view of a trailing dethatcher showing my new design;

FIG. 2 is a front elevational view thereof;

FIG. 3 is a top plan view thereof;

FIG. 4 is a side elevational view thereof, the opposite side being a mirror image;

FIG. 5 is a bottom plan view thereof;

In FIGS. 3-5, the hitch is shown broken away for ease of illustration.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 282,261
